REENFORCING MEANS FOR WOVEN WIRE PANELS

Filed Aug. 19, 1926

INVENTOR.

JOHN R. SCHERER

BY

Rex Foye
ATTORNEY.

UNITED STATES PATENT OFFICE.

JOHN R. SCHERER, OF DETROIT, MICHIGAN, ASSIGNOR TO THE ABBEY-SCHERER COMPANY, A CORPORATION OF MICHIGAN.

REENFORCING MEANS FOR WOVEN-WIRE PANELS.

Application filed August 19, 1926. Serial No. 130,332.

This invention relates to means for reenforcing woven wire panels and the like, and has for its principal object the provision of simple, practical and comparatively inexpensive means for bracing the intermediate portions of wire panels, etc. against strains or impacts that tend to distort the wire itself or bend the members supporting the side edges of the panels.

10 Panels of relatively heavy woven wire are becoming quite generally used for partitioning factory and office space in buildings, etc. since they possess the desired strength, attractiveness and ease of installation and do not obstruct the passage of light, heat and air therethrough. However, it has been found that the intermediate portions of the panels are frequently bumped by passing trucks, persons, etc. or that receptacles, stores, etc. are shifted against the wire with the result that the wire becomes dented or broken and the supporting side strips of the panels bowed or spread. One of the objects of my invention is the arrangement of reenforcing means for such portions of the panels that will brace the panels while providing some resiliency to enable temporary yielding of the panels under the strains imposed.

20 In previous attempts to reinforce the intermediate portions of wire panels it has been proposed to arrange a cross bar between the side bracing strips of the panel, which cross bar passes through horizontal apertures in the side members, and since it is necessary to have the cross-bar of material width for reenforcing purposes it is customary to make the apertures in the side members of almost as great width as the side members themselves, thereby materially decreasing the strength of the side members at the very points where it is intended to reinforce the panels. My invention aims to improve upon these old constructions by providing reenforcing bars of sufficient width and strength so arranged that their ends may be clinched upon the side members of the panel after passing through vertical slots of comparatively little width and arranged substantially centrally of the side members, whereby a sufficient reenforcement of the side members and wire portions of the panel may be secured without materially decreasing the strength of the

side members adjacent the reenforcing bars. 55

Other objects and advantages will be apparent from the following description, wherein reference is made to the accompanying drawings illustrating a preferred embodiment of my invention and wherein similar reference numerals designate similar parts throughout the several views. 60

In the drawings:

Fig. 1 is a front elevation of a partition composed of wire panels reenforced in accordance with my invention. 65

Fig. 2 is an enlarged cross sectional view through one of the panels, taken substantially on the line 2—2 of Fig. 1.

Fig. 3 is a detail perspective view of a 70 tie-bar forming part of my reenforcing means, and

Fig. 4 is a detail perspective view of a 75 spreader-bar forming a part of my improved reenforcing means.

Referring now to the drawings, the numeral 5 designates the wires of a woven wire panel, the wires being herein shown as arranged diagonally in criss-cross relation with their ends secured, as by clinching, 80 within side binding strips 6 and end binding strips 7. For purposes of lightness and strength it is customary to make the binding strips 6 and 7 for the edges of the panels of channel bars with the open sides of the channels extending outwardly. The ends of the wires 5 can then be clinched to secure them in position with the bent ends of the wires within the channels. Suitable means may be employed, as for example angle 85 irons for rigidly securing the end strips 7 to the side strips 6. While it will be obvious that panels of any desired size can be thus constructed it is customary in partitioning factories, etc. to utilize panels of comparatively large size, as for example seven feet high by four feet wide. Such panels can be rigidly secured to the floor and side walls of a building to appropriately position them, and if desired the space between 90 the top of the panels and the ceiling may be left unpartitioned. Also wherever desired suitable hinges may be mounted upon the side members of panels to enable the swinging of the entire panel in the manner of a 95 door, or if preferred one of the panels may be suitably raised and lowered to open and close a passageway through the partition.

105

To withstand strains or impacts upon the intermediate portions of the wire panels I have provided reenforcing means arranged substantially as shown in Fig. 2. A tie-bar 8, preferably crimped or corrugated, is arranged with its extremities extending through substantially vertical slots 9 disposed adjacent the central portions of the web of the channel-bars 6, the portions of the tie-bar extending outwardly beyond the webs of the channel-bars 6 being bent to secure the tie-bar upon the channel-bars 6 through clinching. This tie-bar serves to prevent outward movement of the side strips 6 when strains or shocks are imposed upon the panel and forms a means of carrying a spreader-bar 10, also preferably crimped or corrugated, and arranged with its extremities in abutting relation with the inner surfaces of the side channel-bars 6, substantially as shown in Fig. 2. The tie-bar 8 and spreader-bar 10 are preferably arranged on opposite sides of the wire portion of the panel and secured to each other at predetermined intervals, as by the rivets 11 or other suitable means. The corrugation of the tie and spreader-bars enables the contact of spaced portions of the two bars to facilitate fastening them together, and the portions between such spaced contact points are preferably separated from each other when the rivets 11 have been positioned by a distance slightly less than the thickness of the crossed wires 5 passing between the widened portions of the corrugated bars. Such positioning enables the gripping of the wires themselves by the tie and spreader-bars, strengthening the wires and preventing any chatter when the wire portion of the panel vibrates. The spreader-bar 10 serves to prevent the inward movement toward each other of the side strips 6 when stresses or impacts are imposed upon the intermediate wire portions of the panel.

The simplicity and practicability of my improved reenforcing means is believed to be apparent. The tie-bar 8 effectively holds the side strips 6 against separating movement while the spreader bar 10 as effectively prevents movement of the side strips 6 toward each other. Moreover, the tie-bar 8 provides a simple means of carrying the spreader bar 10 in correct position and its arrangement is such that it may be secured to the side strips 6 with a minimum weakening of the side strips due to slots cut therein. The slots 9 in the side strips are of slightly greater area than the cross section of the tie-bar 8 passing therethrough so as to permit slight movement of the tie-bar upon the side strips when shocks or strains are imposed on the wire portions of the panels. This aids in making the intermediate portions of the panels resilient, and to ward this end the bars 8 and 10 are capable

of slight resilient movements, though the corrugations therein stiffen them as far as practicable.

In practice, I have found it sufficient to use but a single reenforcing means on each panel, arranging such reenforcing means at substantially the height where the panels are most frequently contacted by passing persons, trucks, etc., but it will be obvious that as many reenforcing means may be secured upon a panel as may be desired.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

Having described my invention, I claim:

1. Reenforcing means for a woven wire panel having binding strips at its side edges comprising a tie-bar secured adjacent its extremities to the intermediate portions of said binding strips and a spreader-bar secured to the tie-bar and having its extremities abutting the inner surfaces of the binding strips.

2. Reenforcing means for a woven wire panel having apertured binding strips at its side edges comprising a tie-bar having its extremities extending through the apertures in said binding strips and a spreader-bar secured to the tie-bar and having its extremities abutting the inner surfaces of the binding strips.

3. Reenforcing means for a woven wire panel having apertured binding strips at its side edges comprising a tie-bar having its extremities extending through the apertures in said binding strips and a spreader-bar secured to the tie-bar and having its extremities abutting the inner surfaces of the binding strips, said bars being oppositely corrugated and arranged with the widest portions of their opposed corrugations in engagement with the adjacent wires of the panel.

4. Reenforcing means for a woven wire panel having apertured channel strips at its side edges comprising a tie-bar having its extremities extending through the apertures in said channel strips and then clinched within the channels of said strips and a spreader-bar secured to the tie-bar and having its extremities abutting the inner surfaces of the channel strips.

5. Reenforcing means for a woven wire panel having apertured channel strips at its side edges comprising a tie-bar having its extremities extending through the apertures in said channel strips and then clinched within the channels of said strips and a spreader-bar secured to the tie-bar and having its extremities abutting the inner surfaces of the channel strips, said bars being

corrugated and arranged on opposite sides of the wire portion of the panel.

6. Reenforcing means for a woven wire panel having apertured channel strips at its side edges comprising a tie-bar having its extremities extending through the apertures in said channel strips and then clinched within the channels of said strips and a spreader-bar secured to the tie-bar and having its extremities abutting the inner sur-

faces of the channel strips, said bars being corrugated and arranged on opposite sides of the wire portion of the panel with securing means arranged at spaced intervals for holding said bars in contacting relation and with said bars engaging the wires of the panel intermediate such securing means. 15

In witness whereof I hereunto set my hand.

JOHN R. SCHERER.
